SAFETY RAZOR

Philip H. Borden, Orange, Conn., assignor to Central Industrial Corporation, Memphis, Tenn., a corporation of Tennessee

Original application April 9, 1951, Serial No. 219,950, now Patent No. 2,744,317, dated May 8, 1956. Divided and this application July 3, 1952, Serial No. 297,080

14 Claims. (Cl. 30—60.5)

This invention relates to certain new and useful improvements in safety razors, particularly of the type adapted to employ double edge razor blades. This invention is an improvement upon the inventions of my Patent No. 2,708,310, granted May 17, 1955, and my Patent No. 2,710,447, granted June 14, 1955. This application is a division of my copending application, Serial No. 219,950, filed April 9, 1951, now Patent No. 2,744,317, granted May 8, 1956.

The device involved consists generally of a handle having a blade supporting head rockably attached to the handle and adapted for shift to and from opposite positions of angularity relative to the handle, releasable clamp means cooperating with the head to effect releasable attachment of a razor blade to the head for use, and new and novel means for effecting the shift of the blade clamping means to and from clamping position.

The principal object of the invention is to provide a new and novel safety razor.

A further object of the invention is to provide new and novel blade engaging means and operating means for such blade engaging means cooperating with a blade supporting head to effect desired blade clamping in the safety razor of the invention.

A further object of the invention is to provide blade clamping means respectively pivoted to the blade carrying head along axes longitudinal of the blade carrying head.

A further object of the invention is to provide blade clamping means which are adapted to cooperate with the blade supporting head to effect blade clamping against the head and which are further adapted to effect cover of the upper surface of a blade supported upon said head.

A further object of the invention is to provide such blade clamping covering means with operating means.

A further object of the invention is to provide such operating means, which comprise pinion means carried by the rotatable shafts upon which the respective cover and clamping members are supported, and resiliently mounted rack sections meshing with the pinions to effect opposite rotation thereof upon movement of the rack sections.

A further object of the invention is to provide such a razor having pivotally supported cover members with resilient means cooperatively engaging with the cover members to urge the cover members toward closure and clamping position.

A further object of the invention is to improve the design, construction, and operation of safety razors.

The means by which the foregoing and other objects of the invention are accomplished and the manner of their accomplishment will readily be understood from the following specification upon reference to the attached drawings in which:

Fig. 1 is a perspective view of a preferred form of safety razor.

Fig. 2 is a top plan view of the razor as seen in Fig. 1.

Fig. 3 is a front or edge view of the blade supporting

2

head and related mechanisms with handle broken away.

Fig. 4 is a top plan view of the razor supporting head with the cover clamp members in open position.

Fig. 5 is a sectional view taken as on the line V—V of Fig. 2.

Fig. 6 is an end view of the razor head as seen in Figs. 1, 2 and 3, with parts broken away for illustration.

Fig. 7 is a similar view of the razor head with the cover clamp members open as in Fig. 4.

Fig. 8 is a fragmentary sectional view taken as on the line VIII—VIII of Fig. 3.

Referring now to the drawings, it will be seen that the present invention constitutes an improvement upon the inventions shown and described in my above identified copending applications and that the present invention comprises in general a blade supporting member or razor which is preferably adapted to support double edged razor blades for shaving purposes and includes cover members overlying and retaining a supported blade, and means for mechanically shifting the cover members to release a supported razor blade for removal.

The razor is provided with a handle 11 having at its upper end a yoke 12, the opposite portions or ears of the yoke 12 being preferably rounded to substantially circular shape and being apertured to receive a pin 13, upon which pin is pivoted the neck 14 of a blade supporting head structure 15.

Similar to the construction described in my Patent No. 2,710,447, the lower edge of neck 14 is preferably arcuate, with the arc substantially corresponding in radius to the radius of the yoke portions. Formed in the lower edge of neck 14 are a pair of concavities 16, the concavities 16 being substantially equally spaced from the vertical mid line of neck 14, as best seen in Fig. 6, the spacing being in the nature of twenty-five degrees on either side of the mid line, and the concavities are adapted to be alternatively engaged with a ball 17 mounted in the upper end of a chamber 18 formed in the upper end of handle 11 and urged by a compression spring 19 toward engagement with the lower edge of neck 14. Blade supporting head 15 is, through the medium of neck 14, rockably connected to handle 11; and it may be shifted to opposite positions of angularity relative to handle 11, in which selected positions of angularity ball 17 is urged into engagement with one of the concavities 16, suitably retaining the head in such angular position for use, and it will be observed that such angular position is a desirable shaving angle for use of the razor. In addition, if desired the head 15 may be rocked about its pivotal connection to handle 11 to a position in which the neck 14 is positioned substantially at right angles to the handle, which is frequently desirable, as for example in connection with storage of the razor. In such position, ball 17 is urged by the spring into frictional engagement with the periphery of neck 14 and serves as an effective brake against undesired shift of the head relative to the handle.

Blade supporting head 15 comprises an essentially box-like base 20 which is open at its ends and includes upstanding edge flanges and a flat base plate 21, to which neck 14 is rigidly fixed in perpendicular relation. Overlying base 20 and rigidly connected thereto is a blade seat 22 which is preferably provided with a pair of studs 23, which may be carried by a plate underlying and fixed to the blade seat, as by a screw or other suitable means, the studs being adapted to engage complementary apertures formed in a razor blade B which is preferably adapted for use with the present razor, so as to register the blade with the blade seat for shaving use. Studs 23 lie substantially on the transverse mid-line of blade seat 22 and are preferably substantially equally spaced from the longitudinal mid-line of the blade seat. Blade seat 22 at its opposite edges is provided with down-turned

rounded guard bars 24, at its ends with down-turned flanges 25, and adjacent the guard bars the blade seat is slotted substantially from end to end with elongated slots 26. Adjacent and outwardly from the respective studs 23 a pair of grooves 27 are formed in the blade seat, these grooves being preferably flat and shallow and each extending from one of the slots 26 to the other. The blade seat 22 is thus grooved to provide ready access to the under side of a blade B.

Overlying blade seat 22 are a pair of cover clamp members 28 which preferably each comprise a flat plate-like cover portion adapted to overlie a portion of the blade seat or a blade seated thereon from end to end of the blade head, the two cover members when closed over the blade head meeting substantially along the transverse mid-line of the head and being suitably notched out to accommodate the upstanding studs 23. Each cover member is provided at its opposite sides with tabs 29 which are integral with the cover members and are perpendicular to the cover members. Normally tabs 29 are disposed to closely embrace the opposite side flanges 25 of blade seat 22 and are respectively pivoted to the opposite sides of blade seat 22 as by suitable pins 30, so as to hinge the cover members to the blade head for movement from a closed position, illustrated in Figs. 1, 2, 3, 6 and 8, in which the cover members 28 overlie the blade seat and meet substantially along the transverse mid-line of the blade head, to an open position, illustrated in Figs. 4 and 7, in which cover members 28 have been hingedly swung back about pins 30 so that the covering portions of the cover members are offset from the level of the blade supported head, being thus positioned so as not to impede access to a blade supported upon such head. Each of the cover members is provided with a pinion 31, the pinions 31 being respectively carried by selected pivot pins 30 and being preferably mounted at diagonally opposite corners of blade seat 22 (see Fig. 2), the diagonally opposite corners being preferably inset to accommodate the pinions.

Housed within the box-like base 20 are the manipulatable means by which operation of the covers 28 may be mechanically effected. These manipulatable means each comprise an upstanding rack section 32, each rack section 32 being meshed with one of the pinions 31, with flanges 25 cut off as at 33 to receive the racks, the rack sections being attached to and carried by resilient leaf spring members 34, each spring member 34 being attached at its end remote from its rack section 32 to the under side of blade seat 22, preferably adjacent one end of the blade seat, and being urged by its resilience to diverge away from the under side of the blade seat, being limited in such spring urged movement by engagement with the upper face of the flat base portion 21 of base 20. It will be seen that movement of the racks away from pinion engagement is limited by the flange cut-outs 33.

Upon upward movement of a spring 34 and rack 32 carried thereby from the position as shown in Fig. 3, the interengagement of rack 32 and pinion 31 effects rotation of the pinion and consequently movement of the cover member 28 about its pivotal attachment, moving such cover member toward the open position illustrated in Fig. 7. The resilience of spring member 34 constantly urges return movement of the spring and rack carried thereby and, therefore, urges return of the cover member to closed position, as shown in Fig. 6. In order to provide for ready operation of the spring and rack means, an operating portion 34A of each spring is exposed beyond the sides of base plate 21 for access, such portion preferably comprising the section of springs 34 adjacent their junctions with the rack sections.

Upon the flexing of spring members 34 cover members 28 may be moved to open position so as to provide for access to a blade supported upon blade seat 22. It will also be seen that base 20 with its imperforate base portion 21 and its upstanding edge flanges provides a housing

for the operating means of the device and that the cover members 28 with their flat overlying cover portions and integral end tabs 29 form a completing cover for the blade seat of razor 10. Preferably the tabs 29 which lie adjacent the diagonally opposite racks 32 are each provided with a laterally extending lug 29A which is adapted for engagement to prevent undesired opening movement of the respective cover members.

I claim:

1. Means for operating a cover member used with a razor blade supporting head, which member normally is positioned to overlie said head and is pivoted thereto for movement to and from said overlying position, comprising a pinion connected to said cover member, said pinion being positioned at one end of said head with the upper extent of the pinion lying substantially in the plane of the upper face of said head, spring means secured to and underlying said head, and a rack attached to said spring means and meshing with said pinion, said spring urging said meshed rack and pinion to position said cover member in said overlying position, said spring having an exposed operating portion adapted to be flexed under pressure against said urging to shift said rack and rotate said pinion to move said cover member from said overlying position.

2. Means for operating a pair of cover members used with a razor blade supporting head, which members normally are positioned to overlie said head and are pivoted thereto for movement to and from said overlying position, comprising pinion means respectively connected to each said cover member at diagonally opposite corners of the ends of said cover members, spring means each secured at one end to and underlying said head, the opposite ends of said spring means being exposed and normally spaced from said head, and rack means attached to said spring means adjacent said opposite ends and meshing with said pinion means, said spring means urging said meshed rack and pinion means to position said cover members in said over-lying position, the spaced ends of said spring means being flexed under pressure against said urging to shift said rack means and rotate said pinions to move said cover members from said overlying position.

3. Means for operating a cover member used with a razor blade supporting head, which cover member overlies said head and is pivoted thereto for movement to and from overlying position, comprising a pinion carried by said cover member at one end of said cover member, spring means attached to and underlying said head, a spring-carried rack engaging said cover-carried pinion, said rack being disposed substantially perpendicular to said head and being shiftable along one end of said head, said spring means normally acting in cooperation with said rack to urge said cover member into said overlying position and being flexible against said normal action to effect movement of said cover member away from said overlying position.

4. In a safety razor, a head provided with a seat shaped to support a double-edge razor blade in shaving position, one or more studs projecting upwardly from the seat for interlocking engagement with the blade to index the latter on the seat when positioned against the same, a pair of complementary clamps above the seat movably connected with the head for holding the blade down on the seat, which clamps are movable from blade holding positions into positions wherein the blade is released to permit removal of the same from the seat, each clamp being provided with a pinion mounted adjacent said seat, leaf spring means beneath the seat for normally moving the clamps into their blade holding positions, said spring means being attached to said head at one end and exposed and spaced from said head at the opposite end, and a pair of movable rack members attached to the said spaced ends of said spring means, said rack members being disposed substantially perpendicular to said head and meshed with the clamp pinions for positively moving

the clamps from their blade holding positions into their blade releasing positions upon movement of said spring means against their normal action.

5. In a safety razor, a head provided with a seat shaped to support a double-edge razor blade in shaving position, stud means projecting upwardly from the seat for interlocking engagement with the blade to index the latter on the seat when positioned against the same, a pair of complementary clamps above the seat movably connected with the head for holding the blade down on the seat, which clamps are movable from blade holding positions into positions wherein the blade is released to permit removal of the same from the seat, resilient means beneath the seat for normally moving the clamps into their blade holding positions, and a pair of pinion members beneath the seat respectively connected with the clamps for positively moving the latter from their blade holding positions into their blade releasing positions, which pinion members are separately movable and are separately connected with the clamps, whereby either of the clamps may be moved independently of the other into its blade releasing position.

6. In a safety razor which includes a horizontal head for supporting a razor blade and cover members respectively pivotally connected to the opposite sides of said head for movement to and from a clamping position, in which each said cover member overlies said head, from and to open positions, in which said members are shifted away from said head, a pair of pinions respectively connected to said cover members and disposed at the opposite ends of said head, the upper extent of the periphery of said pinions lying substantially in the plane of the upper face of said head, a pair of leaf spring members respectively attached at one end to the under surface of said head, the opposite ends of said spring members being spaced from said under surface, a pair of upstanding rack sections respectively connected to said opposite ends of the spring members and lying alongside said head ends in mesh with said pinions, said rack sections being shiftable independently in a substantially vertical direction, to effect movement of either cover member independently of the other cover member, said spring members urging shift of said rack sections to move said cover members toward said clamping position.

7. In a safety razor which includes a head for supporting a razor blade and cover members respectively pivotally connected to the opposite sides of said head for movement to and from a clamping position, in which each said cover member overlies said head, from and to open positions, in which said members are shifted away from said head, a pair of pinions respectively connected to said cover members, said pinions being disposed at diagonally opposite corners of the ends of said head, said head being inset at said corners to receive said pinions, the upper extent of the periphery of said pinions lying substantially in the plane of the upper face of said head, a pair of leaf spring members respectively attached to the under surface of said head, a pair of upstanding rack sections respectively connected to said spring members and lying alongside said head ends in mesh with said pinions in a plane substantially perpendicular to the plane of said head upper face.

8. In a safety razor which includes a horizontal head for supporting a razor blade and cover members respectively pivotally connected to the opposite sides of said head for movement to and from a clamping position, in which each said cover member overlies said head, from and to open positions in which said members are shifted away from said head, a pair of pinions respectively connected to said cover members, said pinions being disposed at diagonally opposite corners of the ends of said head, the upper extent of the periphery of said pinions lying substantially in the plane of the upper face of said head, a pair of leaf spring members respectively attached at one end to the under surface of said head adjacent the

other corners of the ends of the head, said spring members extending substantially the length of said head with the opposite ends of said spring members spaced from said under surface, a pair of substantially vertical rack sections respectively being connected to said opposite ends of the spring members and lying along side said head ends in mesh with said pinions, said rack sections being independently vertically reciprocable with said spring members to effect movement of either cover member independently of the other cover member, said spring members urging shift of said rack sections to move said cover members toward said clamping position.

9. In a safety razor which includes a head for supporting a razor blade and cover members respectively pivotally connected to the opposite sides of said head for movement to and from a clamping position, in which each said cover member overlies said head, from and to open positions in which said members are shifted away from said head, a pair of pinions respectively connected to said cover members, said pinions being disposed at diagonally opposite corners of the ends of said head, said head being inset at said corners to receive said pinions, the upper extent of the periphery of said pinions lying substantially in the plane of the upper face of said head, a pair of leaf spring members respectively attached at one end to the under surface of said head adjacent the other corners of the ends of the head, said spring members extending substantially the length of said head with the opposite ends of said spring members spaced from said under surface, a pair of upstanding rack sections respectively being connected to said opposite ends of the spring members and lying along side said head ends in mesh with said pinions in a plane substantially perpendicular to the plane of said head upper face.

10. In a safety razor which includes a horizontal head for supporting a razor blade and cover members respectively pivotally connected to the opposite sides of said head for movement to and from a clamping position, in which each said cover member overlies said head, from and to open positions in which said members are shifted away from said head, a pair of pinions respectively connected to said cover members, said pinions being disposed at diagonally opposite corners of the ends of said head, said head being inset at said corners to receive said pinions, the upper extent of the periphery of said pinions lying substantially in the plane of the upper face of said head, a pair of leaf spring members respectively attached at one end to the under surface of said head adjacent the other corners of the ends of the head, said spring members extending substantially the length of said head with the opposite ends of said spring members spaced from said under surface, a pair of substantially vertical, upstanding rack sections respectively being connected to said opposite ends of the spring members and lying along side said head ends in mesh with said pinions in a plane substantially perpendicular to the plane of said head upper face, said rack sections being independently vertically shiftable with said spring members to effect movement of either cover member independently of the other cover member, said spring members urging shift of said rack sections to move said cover members toward said clamping position.

11. In a safety razor which includes a head for supporting a razor blade and cover members respectively pivotally connected to the opposite sides of said head for movement to and from a clamping position, in which each said cover member overlies said head, from and to open positions, in which said members are shifted away from said head, a pair of pinions respectively connected to said cover members, a pair of leaf spring members respectively attached to the under surface of said head, a pair of upstanding rack sections respectively connected to said spring members and lying alongside said head in mesh with said pinions, said rack sections being shiftable independently in a substantially vertical direction, to

effect movement of either cover member independently of the other cover member, said spring members urging shift of said rack sections to move said cover members toward said clamping position.

12. In a safety razor which includes a head for supporting a razor blade and cover members respectively pivotally connected to the opposite sides of said head for movement to and from a clamping position, in which each said cover member overlies said head, from and to open positions, in which said members are shifted away from said head, a pair of spring members respectively attached to the under surface of said head, means located respectively at the opposite ends of said head operatively interconnecting said springs to said cover members, said springs and said means being shiftable independently in a substantially vertical direction, to effect movement of either cover member independently of the other cover member, said spring members urging shift of said means to move said cover members toward said clamping position.

13. In a safety razor which includes a head for supporting a razor blade and cover members respectively pivotally connected to the opposite sides of said head for movement to and from a clamping position, in which each said cover member overlies said head, from and to open positions, in which said members are shifted away from said head, a pair of rotatable elements respectively connected to said cover members and positioned at diagonally opposite corners of said head, spring means attached to the under surface of said head, a pair of sections for rotating said elements respectively connected to said spring

means and engaged with said rotatable elements, said sections being shiftable independently relative to said head, to effect movement of either cover member independently of the other cover member, said spring means urging shift of said cover members toward said clamping position.

14. In a safety razor which includes a head for supporting a razor blade and a cover member pivotally connected to one side of said head for movement to and from a clamping position, in which said cover member overlies said head, from and to an open position, in which said member is shifted away from said head, a pinion connected to said head, a spring member attached to the under surface of said head, an upstanding rack section connected to said spring member and lying alongside said head in mesh with said pinion, said rack section being shiftable in a direction substantially perpendicular to said head, to effect movement of said cover member, said spring member urging shift of said rack section to move 20 said cover member toward said clamping position.
